UNITED STATES PATENT OFFICE.

ALVIN J. MUSSelman, OF CHICAGO, ILLINOIS.

DESIGN FOR A COASTER-BRAKE HUB.

No. 39,692.

Specification for Design.

Patented Dec. 15, 1908.

Application filed May 4, 1908. Serial No. 430,871. Term of patent 7 years.

To all whom it may concern:

Be it known that I, ALVIN J. MUSSelman, a citizen of the United States, residing at Chicago, in the county of Cook and State of Illinois, have invented a new, original, and ornamental Design for Coaster-Brake Hubs, of which the following is a specification, reference being had to the accompanying drawing, forming part hereof.

The figure is a perspective view of a coaster-brake hub, showing my new design.

The salient feature of the design is that of

the spaced annular ribs encircling the hub augment its exterior surface-area and thus greatly add to its ornamentation by enhancing the attractiveness of the fancy finish which gives it its polished appearance.

I claim:

The ornamental design for a coaster-brake hub, as shown and described.

ALVIN J. MUSSelman.
